(57) **CLAIM**

The ornamental design for a fragrance bottle, as shown and described.

DESCRIPTION

FIG. 1 is a top, front and right side perspective view of a first embodiment of our new design for a fragrance bottle;

FIG. 2 is a front elevation view of the fragrance bottle shown in FIG. 1, the rear elevation view being identical thereto;

FIG. 3 is a right side elevation view of the fragrance bottle shown in FIG. 1, the left side elevation view being identical thereto;

FIG. 4 is a top plan view of the fragrance bottle shown in FIG. 1;

FIG. 5 is a bottom plan view of the fragrance bottle shown in FIG. 1;

FIG. 6 is a top, front and right side perspective view of a second embodiment of our new design for a fragrance bottle;

FIG. 7 is a front elevation view of the fragrance bottle shown in FIG. 6, the rear elevation view being identical thereto;

FIG. 8 is a right side elevation view of the fragrance bottle shown in FIG. 6, the left side elevation view being identical thereto;

FIG. 9 is a top plan view of the fragrance bottle shown in FIG. 6;

FIG. 10 is a bottom plan view of the fragrance bottle shown in FIG. 6;

FIG. 11 is a top, front and right side perspective view of a third embodiment of our new design for a fragrance bottle; FIG. 12 is a front elevation view of the fragrance bottle shown in FIG. 11, the rear elevation view being identical thereto;

FIG. 13 is a right side elevation view of the fragrance bottle shown in FIG. 11, the left side elevation view being identical thereto;

FIG. 14 is a top plan view of the fragrance bottle shown in FIG. 11; and,

FIG. 15 is a bottom plan view of the fragrance bottle shown in FIG. 11.

The broken lines are shown for the purpose of illustrating unclaimed portions of the fragrance bottle and form no part of the claimed design.
